UNITED STATES PATENT OFFICE

ZIVKO MILOS AND KOSTA MARKOVICH, OF DETROIT, MICHIGAN

BRUSH FOR BOTTLE-WASHING MACHINES

Application filed October 27, 1927. Serial No. 229,058.

Our invention relates to a mechanically actuated brush for washing bottles, especially bottles of five or ten gallon capacity, shown in the accompanying drawings and more particularly described in the following specification and claims.

One object of this invention is to provide a brush adapted to be collapsed that it may enter the neck of a bottle and then expanded that the bristles of the brush may contact with the inner wall of the bottle to scrub the latter.

A further object of the invention is to combine with the frame of the brush a pipe connection for the introduction of a cleansing fluid into the bottle while rotating the brush to scrub the latter.

A further object of the invention is to provide a plurality of radiating collapsible frames hinged to a slidable tube sleeved upon a pipe or nozzle through which water or other fluid is introduced into the bottle to be cleansed,—the construction being such that the several hinged radiating arms and bars of the folding brush may be simultaneously collapsed or opened by a longitudinal movement of said slidable tube upon the pipe or nozzle.

A further object of the invention is to provide a device adapted to be mechanically rotated and the folding frame of the brush automatically collapsed sufficiently to pass through the neck of a bottle and then automatically opened that the bristles of the brush may contact with the walls of the bottle,—the operation being such that either the collapsible brush when opened may be shifted longitudinally within the bottle while rotating, or the bottle may be shifted longitudinally in relation to the brush, the brush being then automatically collapsed for withdrawal from the bottle following a pre-determined period allowed for the scrubbing operation;—the mechanism actuating the brush for performing these several operations being the subject matter of another application.

With the foregoing and other objects in view which will appear as the description proceeds, the invention further resides in the combination and arrangement of parts and in

the details of construction hereinafter described and claimed, it being understood that changes may be made in the precise embodiment of the invention herein disclosed without departing from the spirit of the same. 55

In the drawings accompanying this specification:

Figure 1 is a side elevation of the brush with parts broken away and in section, showing in full lines the brush in its open position 60 and in dotted lines, its collapsible portion closed for withdrawal from a bottle.

Figure 2 is a perspective view of a modification of the device, in which four radiating brush arms are employed instead of two,—as 65 disclosed in the preceding view.

Figure 3 is a diagrammatic view showing the brush expanded within a bottle,—indicated in dotted lines,—and also indicating diagrammatically, means for mechanically rotating the brush and for longitudinally shifting it that the device may be collapsed for removal or entry through the neck of a bottle. 70

Figure 4 is a diagrammatic cross-sectional view taken on or about line 4—4 of Figure 3. 75

Figure 5 is an elevation of the cam,—shown partially broken away in Figure 3, as viewed from about line 5—5,—for longitudinally shifting and collapsing the frame of the brush. 80

Figure 6 is a cross-sectional view taken on or about line 6—6 of Figure 3, showing diagrammatically, means for rotating the longitudinally slid able member sleeved on the pipe or nozzle. 85

Figure 7 is a fragmentary longitudinal sectional view taken on or about line 7—7 of Figure 1, indicating an abutment or stop provided on the nozzle to limit the movement of the slid able member controlling the opening 90 and closing of the brush.

At this point it may be stated that the several diagrammatic views—Figures 4 to 6—are designed to make clear the respective corresponding elements indicated in Figure 3. 95

Referring now to the letters of reference placed upon the drawings:

A denotes a pipe or nozzle of rectangular form in cross-section having at its forward end reduced apertures *a* through which water 100

or other cleansing fluid may be injected into a bottle under pressure.

B is a sleeve member of similar form in cross-section having a limited slideable movement upon the pipe or nozzle.

5 C, C are brush supporting arms—pivoted at C¹ to the member B—having lugs C², extending at right angles to the arms to limit the swinging movement of the latter upon the lugs contacting with the wall of the nozzle.

10 D, D are similar brush arms pivoted at D¹, D² to the forward end of the nozzle.

E, E are connecting brush bars respectively pivoted to the arms C, C and D, D at 15 their outer ends.

F indicates bristles set in the arms C, D, and their connecting bars.

20 A¹ is a raised abutment formed on the nozzle A to limit the movement of the slideable member.

G denotes a circular disc carried by the member B which is adapted to rotate in a groove formed in a slideable element H supported in suitable guideways I^a, I^a.

25 The slideable element H has a pin H¹ projecting into a groove I¹ formed in a cam I mounted on a shaft J, journaled in bearings J¹ for supporting the shaft.

B^a denotes a relatively long circular sleeve 30 on the end of the slideable member B, driven by a frictional driving disc K on the shaft K¹, journaled in bearings K² for supporting the latter.

The sleeve B^a connected with the slideable member B may be rotated by the frictional driving disc K while it is being shifted longitudinally upon the nozzle A to open and close the brush frame,—it being noted that the rectangular shaped nozzle A has a circular formation at A^a adjacent its inner end 40 fitted with a circular collar A^b,—the circular end of the nozzle extending through the coupling nut L, which is in turn screwed to a supply pipe M,—the nozzle being thus free 45 to turn with the brush.

N indicates a washer lodged within the coupling nut to provide against leakage. P denotes a bottle indicated in dotted lines, with the brush expanded therein.

50 In the modification shown in Figure 2, instead of a single collapsible brush frame as indicated in Figure 1, a second frame of similar construction but projecting at right angles to the other frame is shown,—otherwise the construction and operation of the device is identical with that shown in the preceding figure.

In Figure 3 is graphically illustrated means 60 for mechanically operating the brush whereby it may be collapsed to permit entry or withdrawal through the neck of a bottle,—also means for rotating the brush when inserted in the bottle.

65 Having indicated the several parts by ref-

erence letters, the construction and operation of the device will be readily understood.

To insert the brush in the bottle, the slideable member B is shifted through the operation of the cam I to a position indicated by dotted lines in Figure 1, in which the several jointed brush bars lie adjacent to the wall of the nozzle. The brush may then be inserted in the neck of the bottle or the bottle pushed over the brush as will be dependent upon the particular construction and operation of the machine in which the brush forms a part.

Upon the rotation of the cam the jointed frame carrying the brush bristles will be expanded within the bottle that it may contact with and scrub the walls of the latter, the water or other cleansing fluid entering the bottle simultaneously with the rotation of the brush.

Any suitable means may be provided, if desired, for actuating the brush in the cleansing of a bottle or similar container.

It will be noted that the pipe or nozzle A and the sleeve B thereon are described as being of rectangular form in cross section. This enables the elements to be more readily fitted together, more easily actuated with respect to one another and further produces a more compact structure. Still further, this construction permits spaces to be provided on the elements against which other movable elements and their adjunctive parts may fit flatly and produce a most compact device when collapsed.

Having thus described our invention what we claim is:

1. In a brush of the character described, a pipe of rectangular form in cross-section provided at one end with a restricted discharge opening; a movable element rectangular in cross-section and longitudinally slideable in relation to said pipe; and a plurality of bars linked together fitted with bristles to form brushes, the linked brush members being respectively hinged at one end to the pipe and at the other end to the movable element, whereby upon sliding said movable element longitudinally in relation to the pipe, the linked brush bars may be either shifted in spaced relation to the pipe or forced adjacent thereto.

2. In a brush of the character described, a pipe nozzle rectangular in cross section; a movable element of similar cross sectional design sleeved upon the said pipe nozzle; a plurality of bars linked together and fitted with bristles to form brushes, the linked brush members being respectively hinged at one end to the pipe nozzle and at the other end to the movable element; and means on said nozzle for limiting the movement of the slideable element in relation to the pipe nozzle.

3. In a brush of the character described, a pipe nozzle rectangular in cross section; a

- movable element of similar cross sectional design sleeved upon the pipe nozzle and longitudinally slidable in relation to the latter; a plurality of bars fitted with bristles 5 to form brushes and linked together, said linked members being respectively hinged at one end to the pipe nozzle and at the other end to the movable element; means carried by said bars to limit their swinging movement; and means on said nozzle for limiting the movement of the slidable member upon the pipe nozzle.
4. In a brush of the character described, a pipe nozzle rectangular in cross section; a 15 movable element of similar cross sectional design sleeved upon said pipe nozzle; a plurality of members linked together fitted with bristles to form brushes, the respective linked members being pivoted at one end to the pipe 20 nozzle and at the other end to the slidable element; mechanical means for longitudinally shifting the movable element, whereby the linked brush members may lie adjacent to the pipe nozzle or be forced in spaced relation to the latter; and means for rotating said brush.
5. In a brush of the character described, a pipe nozzle rectangular in cross-section; a movable element rectangular in cross-section 30 sleeved upon said pipe nozzle; a plurality of members linked together fitted with bristles to form brushes, the respective linked members being pivoted at one end to the slid- 35 able element; and mechanical means for longitudinally shifting the movable element, whereby the linked brush members may lie adjacent to the pipe nozzle or be forced in spaced relation to the latter; and means for rotating said brush.
- 40 6. In a brush of the character described, a pipe member rectangular in cross-section and provided with restricted exit openings at the outer end thereof, a sleeve member rectangular in cross-section and slidably 45 mounted on said pipe member, a pair of brush supporting elements each composed of a series of linked-together bars, the outer end bars of said elements being hinged respectively to opposite sides of the pipe member at the outer 50 end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
7. In a brush of the character described, a pipe member rectangular in cross-section and provided with restricted exit openings at the outer end thereof, a sleeve member 55 rectangular in cross-section and slidably 60 mounted on said pipe member, a pair of brush supporting elements each composed of a series of linked-together bars, the outer end bars of said elements being hinged respectively to opposite sides of the pipe member at the outer 65 end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
8. In a brush of the character described, a pipe member rectangular in cross-section and provided with restricted exit openings at the outer end thereof, a sleeve member 70 rectangular in cross-section and slidably 75 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
9. In a brush of the character described, a pipe member rectangular in cross-section and provided with restricted exit openings at the outer end thereof, a sleeve member 75 rectangular in cross-section and slidably 80 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
10. In a brush of the character described, a pipe member rectangular in cross-section and provided with restricted exit openings at the outer end thereof, a sleeve member 85 rectangular in cross-section and slidably 90 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
11. In a brush of the character described, a pipe member rectangular in cross-section and provided with restricted exit openings at the outer end thereof, a sleeve member 95 rectangular in cross-section and slidably 100 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
12. In a brush of the character described, a pipe member rectangular in cross-section and provided with restricted exit openings at the outer end thereof, a sleeve member 105 rectangular in cross-section and slidably 110 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
13. In a brush of the character described, a pipe member rectangular in cross-section and provided with restricted exit openings at the outer end thereof, a sleeve member 115 rectangular in cross-section and slidably 120 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
14. In a brush of the character described, a pipe member rectangular in cross-section and provided with restricted exit openings at the outer end thereof, a sleeve member 125 rectangular in cross-section and slidably 130 mounted on said pipe member, a pair of brush supporting elements each composed of a series of linked-together bars, the outer end bars of said elements being hinged respectively to opposite sides of the pipe member at the outer end of the latter, the opposite end bars of the elements being respectively pivoted to opposite sides of the outer end of said sleeve member, stop members carried on said pipe member to limit the outward sliding movement of the sleeve member on said pipe member, as and for the purposes described.
